UNITED STATES PATENT OFFICE.

JOSEPH R. HAWLEY, OF HARTFORD, CONNECTICUT, AND HARRIS P. HURST,
OF SUMMIT, MISSISSIPPI.

PROJECTILE.

SPECIFICATION forming part of Letters Patent No. 388,413, dated August 28, 1888.

Application filed October 10, 1887. Serial No. 251,955. (No model.)

To all whom it may concern:

Be it known that we, JOSEPH R. HAWLEY, residing at Hartford, Hartford county, Connecticut, and HARRIS P. HURST, residing at 5 Summit, in the county of Pike and State of Mississippi, have invented certain new and useful Improvements in Projectiles, of which the following is a specification, reference being had therein to the accompanying drawings.

10 This invention relates to projectiles for rifled guns.

The invention consists in the construction and combination of the parts constituting the projectile.

15 The object of the invention is to produce a projectile which will take the rifling of the gun with certainty, and in which the guiding-sabot shall offer little resistance to the flight of the projectile; also to produce a base-burning time-fuse which will be protected by the sabot.

20 Heretofore there has been difficulty in producing a reliable time-fuse to apply to the base of a shell, owing largely to the fact that the intense heat of the explosion of the firing-charge in the gun will cause too rapid combustion of the fuse-charge. This objection is largely or entirely overcome in this invention by the tight-sealing sabot which protects the fuse-charge. It will thus be seen that there is 25 a direct co-operation between the sabot and the fuse employed.

30 In the drawings, Figure 1 is a side elevation, partly sectioned, of a projectile having detachable sabot. Fig. 2 is a similar view of a projectile with detaching-spring omitted. Fig. 3 is an elevation of one of the rings of the sabot. Fig. 4 is a longitudinal central section of a shell with sabot and fuse applied. Fig. 5 is a similar section of a modification. Fig. 6 is a 35 plan of the time-regulating plug of the shell. Fig. 7 is a side elevation, partly sectioned, of the same.

40 A indicates the body of the projectile or shell. This part of the projectile is of any usual form. The projectile has a sabot composed externally of a series of washers, B, of leather, compressed paper, or similar material. These washers B are applied to a central core-piece, C, (of metal by preference,) and detachable from the body A of the projectile. The

core-piece may enter a hole in the body of the projectile, as in Figs. 1 and 2, or the core-piece may be cupped and serve as a cover to a projecting seat at the base of the projectile, as in Figs. 4 and 5. This reversal of parts is considered an equivalent construction. There may be a spring, D, interposed between the core-piece and the projectile where the taper of the core-piece is not great enough to cause the sabot to drop from the projectile by the 55 resistance offered by the atmosphere during the flight of the projectile. The core-piece may be surrounded by the layer E, of oiled paper or similar material, to prevent binding and avoid the necessity of a fine finish to the 60 metallic surfaces. The disks B are of such diameter as to fill the bore of the gun and take the rifling. The disks will prevent the flash of the explosion reaching forward past the base of the projectile, as well as cause the projectile to rotate as the disks take the rifling. The core-piece C may be a little out of true, or may be of any form that will engage the projectile in such manner as to cause the two 65 to rotate together. 70

75 As shown in Figs. 4 and 5, a time-fuse is placed in front of the core-piece C, and the forward movement of the core-piece, when the explosion takes place, ignites this fuse through the explosion of a fulminate-cap, F. The core C may be held against accidental explosion of the cap by a pin, G, which locks the core and projectile together, but is sheared off by the shock of the explosion and permits the core to move forward. 80

85 In front of the cap F there is a channel, H, leading to the charge-chamber M of the projectile. This channel is cut off by a plug, I, which has a groove, K, running nearly around its outer surface in line with channel H. The 90 groove K communicates with a channel, L, running to the center of the plug, and so to a connection with the bursting charge. The groove K is filled with slow-burning powder, which may be covered with a film of collodion or a 95 sheet of foil or prepared paper. The plug I is held in its seat in a hole crossing the channel H by means of a cap, N. The plug can be turned by a screw-driver or other instrument, so that any part of the groove K can be brought 100

opposite the passage H. An index on the outer end of plug I enables the gunner to distinguish the position of the groove K with relation to the channel H. When the plug is turned so that the channel H is in line with the end of groove K farthest from passage L, the slow powder must burn the whole length of channel K before it can ignite the bursting charge through passage L; but when the plug is turned so that the channel H is in line with the groove K near the passage L the slow powder in the rest of the groove will burn very quickly and ignite the charge after a very short interval. Thus the time of the burning of the fuse may be regulated with great exactness by the turning of the plug I, the distance between the channel H and passage L to be burned determining the time after firing the gun before the explosion of the shell.

The charge in channel H may be small, just enough to ignite the fuse composition in channel K; but by increasing this charge the escaping gas will tend to blow the sabot from the projectile after the pressure of the firing charge ceases, the escaping gas thus assisting the spring D to free the projectile from the sabot. In any case the charge in channel H will be too small to drive in the slow-burning powder in groove K, as might happen if the charge in the gun were in communication with the fuse-powder.

We claim—

1. The combination, with a projectile having a movable sabot, of a cap in front of the sabot

and a time-fuse having a revoluble plug between the cap and bursting charge, said plug having a time-charge in a groove in front of the cap, substantially as described.

2. The combination, with the projectile, of the movable sabot consisting of a central core surrounded by rings, a pin connecting the core and body of the projectile, a cap in front of the core-piece, and a time-fuse having a revoluble plug provided with a burning charge connecting the cap and bursting charge of the shell, substantially as described.

3. The combination, with a projectile, ring-sabot, and core-piece on which the rings are mounted, of a pin connecting the core and sabot in such manner that the pin is sheared off in firing the gun, substantially as described.

4. The combination, with a projectile, of a sabot consisting, essentially, of rings or washers, the rings gradually increasing in diameter from front to rear, substantially as shown.

5. The combination, with a projectile, of a series of leather washers gradually increasing in diameter toward the rear and surrounding a core-piece, said core-piece being attached to the projectile, substantially as described, so as to compel the rotation of the projectile.

In testimony whereof we affix our signatures in presence of two witnesses.

JOS. R. HAWLEY.
HARRIS P. HURST.
